UNITED STATES PATENT OFFICE

137,526

DESIGN FOR A COMBINED CAN AND BOTTLE OPENER

Jacob Rashi, Zanesville, Ohio

Application January 19, 1944, Serial No. 112,269

Term of patent 14 years

(Cl. D44—29)

To all whom it may concern:

Be it known that I, Jacob Rashi, a citizen of the United States, residing at Zanesville, in the county of Muskingum and State of Ohio, have invented a new, original, and ornamental Design for a Combined Can and Bottle Opener, of which the following is a specification, reference being had to the accompanying drawing, forming part thereof.

Figure 1 is a bottom plan view of a combined can and bottle opener, showing my new design; Figure 2 is a side elevational view; and Figure 3 is a front elevational view thereof.

I claim:

The ornamental design for a combined can and bottle opener, as shown.

JACOB RASHI.
